(57) **CLAIM**

We claim the ornamental design for an infant nurser, as shown and described herein.

DESCRIPTION

FIG. 1 is a top perspective view of an infant nurser, showing our new design;

FIG. 2 is a top plan view thereof;

FIG. 3 is bottom plan view thereof;

FIG. 4 is a right side elevational view thereof; and,

FIG. 5 is a left side elevational view thereof.

The broken lines shown in FIGS. 1-5 are for illustrative purposes only and form no part of the claimed design.
